UNITED STATES PATENT OFFICE.

JOHN C. BORN, OF BELLEVILLE, ILLINOIS.

STEAM PUMPING-ENGINE.

SPECIFICATION forming part of Letters Patent No. 322,784, dated July 21, 1885.

Application filed November 28, 1884. (No model.)

To all whom it may concern:

Be it known that I, JOHN C. BORN, of Belleville, in the county of St. Clair and State of Illinois, have invented a certain new and useful Improvement in Steam Pumping-Engines, of which the following is a full, clear, and exact description, reference being had to the accompanying drawings, forming part of this specification, and in which—

- 10 Figure 1 is an elevation, and Fig. 2 a top view, of my improved engine, showing its application to a pump. Fig. 3 is an end view of same. Fig. 4 is a longitudinal section, taken on line 4 4, Fig. 3. Fig. 5 is a detail section, taken on line 5 5, Fig. 4. Fig. 6 is a detail view of the pump-barrel. Fig. 7 is an elevation of the discharge-valve. Fig. 9 is a similar view of the receiving-valve, and Fig. 8 is an elevation of the valve-cage.
- 20 My invention relates to a steam or other engine particularly adapted to boiler-feeders; and my invention consists in features of novelty hereinafter fully described, and pointed out in the claims.
- 25 Referring to the drawings, A represents the cylinder; B, the cylinder-heads; C, the steam-chest formed in the front cylinder-head; D, the piston in the cylinder A; I, the piston-rod; J, the valve in the chest C; J', the valve-stem; L, a bracket secured to the cylinder to guide the valve-stem; M, a shaft journaled in lugs M', formed upon the head of the cylinder in which the steam-chest is located; N, a fly-wheel on the shaft M; O, a cam on the shaft 30 having an eccentric groove to receive a projection, J², on the valve-stem, which may be surrounded by a friction-roller, J³; P, a disk on the shaft; P', an eccentric wrist-pin on the disk; P², a rod connecting the wrist-pin with a cross-head, I', on the piston-rod, by which the shaft M is turned to operate, through means of the described connection, the valve in the steam-chest; A², the supply-ports, and A³ the exhaust-port.
- 45 The steam-chest and valve are preferably circular, as shown in Fig. 4, and the valve has a recess, J⁴, to permit the exhaust-steam to enter the port A³. The back of the valve-stem has a projection, J⁵, that fits in a groove, L', of the bracket L. The piston-rod acts as the plunger of the pump, entering a barrel, U,

provided with a stuffing-box, U', and a disk or flange, U², connected by arms U³ to the rear head of the cylinder.

V represents the pump-cylinder, secured to 55 the barrel U by a bolt, V', and the interior of which communicates with the interior of the barrel by openings or perforations V². (See Figs. 4 and 6.)

Within the cylinder is a cage, W, having 60 perforations W' for the passage of the water, and in which is seated a receiving-valve, W², and discharge-valve W³. The cage is preferably formed on the inner end of a plug, W⁴, that screws into the cylinder. 65

X represents the water-supply and X' the water-discharge opening, with which suitable pipes are connected.

The inner end of the cage has a collar, W⁵, fitting against a flange, W⁶, on the interior of 70 the cylinder.

A bracket, Y, may be formed upon one of the arms U³ to secure the device to a support.

The cylinder V may be turned to any position to receive the water-supply pipe, as shown 75 by full and dotted lines, Fig. 1, the joint between it and the barrel U permitting of this adjustment, as will be clearly understood by referring to Fig. 4.

A⁴ represents the pipe for the supply of 80 motive power, which may be steam or air.

I have not claimed in this application any of the novel features which the pump herein described may possess, but reserve the right to make said pump the subject of a separate 85 application for Letters Patent.

I am aware that steam-valves have been operated from the main shaft of the engine through the medium of an eccentric wrist-pin carried by said shaft, and a pitman connecting it with the stem of the valve; but such is not the equivalent of my invention. 90

I claim as my invention—

1. The combination, with the cylinder A, having the reciprocating piston D, of the 95 steam-chest C, located at the end of said cylinder and transversely thereto, a slide-valve, J, located in said chest and having a stem projecting therefrom, a rotary shaft, M, journaled externally to the cylinder and chest and parallel with the movement of the valve, a cam, O, carried by said shaft, and a lateral

projection from the valve-stem with which said cam engages to move the valve, as set forth.

2. The combination, with the cylinder A, 5 the reciprocating piston D, and the piston-rod I, of the steam-chest C, located transversely to and at the end of said cylinder, the slide-valve J, having the stem projecting from said chest and provided with lateral projections J², the

rotary shaft M, journaled externally to said cylinder and chest and parallel to the latter, the cam O, carried thereby, the wrist-pin P, and connecting-link P², all constructed and arranged to operate substantially as set forth.

JOHN C. BORN.

In presence of—

CHARLES BORN,
GEO. H. KNIGHT.
